(57) **CLAIM**

The ornamental design for a parking kiosk, as shown and described.

DESCRIPTION

FIG. 1 is a front perspective view of a parking kiosk according to a first exemplary embodiment of the present design;

FIG. 2 is a right elevational view of the parking kiosk shown in FIG. 1;

FIG. 3 is a left elevational view of the parking kiosk shown in FIG. 1;

FIG. 4 is a front elevational view of the parking kiosk shown in FIG. 1;

FIG. 5 is a rear elevational view of the parking kiosk shown in FIG. 1;

FIG. 6 is a top plan view of the parking kiosk shown in FIG. 1; and,

FIG. 7 is a bottom plan view of the parking kiosk shown in FIG. 1.

Applicant respectfully submits that the broken or dashed line format lines shown herein are for illustrative purposes only and form no part of the claimed design.

1 Claim, 5 Drawing Sheets
